UNITED STATES PATENT OFFICE.

ISAAC E. KALISHER, OF NEW YORK, N. Y., ASSIGNOR TO KALISHER MFG. CO., OF NEW YORK, N. Y., A FIRM COMPOSED OF SAMUEL WEIN, LOUIS LEOPOLD, AND ISAAC E. KALISHER.

JEWELRY.

Application filed April 8, 1925. Serial No. 21,547.

To all whom it may concern:

Be it known that I, ISAAC E. KALISHER, citizen of the United States of America, residing at city, county, and State of New York, have invented new and useful Improvements in Jewelry, of which the following is a specification.

My invention relates to improvements in jewelry, and is especially concerned with 10 such articles of jewelry as finger rings.

The object of the invention is to provide a construction by which one and the same article of jewelry may be provided with various kinds of inserts such as emblems, 15 designs or ornaments, thus changing the general appearance of the article of jewelry as may be desired.

I accomplish the object of my invention by removing from the completed article of 20 jewelry a portion in the desired position to leave a space into which the insert may be placed and where it may be removably secured. In my co-pending patent application No. 736,709 filed September 9th, 1924

25 I disclose a method of manufacturing jewelry according to which I cut or remove from the completely formed article a portion thereof to form a space and thereafter secure in said space a desired design or 30 ornamentation. In the application referred to, it is contemplated that the inserted member shall be soldered in position, thus providing for a fairly permanent attachment of the insert, while according to my present 35 invention, which is a development of the former, the purpose is to so attach the inserted member in the space, as to make it readily removable so that the inserted members or inserts are interchangeable thereby 40 providing the possibility of almost unlimited changes in appearance of the piece of jewelry as a whole. The invention is illustrated in the accompanying drawing in which:

45 Figure 1 is a side elevational view of an ordinary finger ring with an insert in position; Figure 2 is a side elevational view of a finger ring and an insert in proximity thereto, and Figure 3 is a view similar to 50 Figure 2 of a modified form of the invention.

While the drawing shows a ring as the article to which my invention is applied, it will be understood that the invention may 55 be used with equal facility in a great many

articles of jewelry such as brooches, bar pins, pendants and the like.

From an ordinary finger ring 10, I remove a section or part which may be curved, so that the space 11 resulting from the removal of such portion is curved. In the 60 illustrated forms of the invention, the insert is provided with suitable means for detachably engaging anchoring means in the space in which the insert is placed.

The insert 12 in Figure 2 of the drawing is provided at each end with fine inwardly directed prongs 13, there being preferably two prongs at or near each end of the insert. In the space 11 are two anchoring 70 posts 14, one near each end of the space, and to secure the insert in position the prongs 13 are clinched or bent about the anchoring posts. Although the work is fine it is simple and can be quickly done by a 75 person having very little skill. If it be desired to remove the insert, the prongs 13 are unclinched or straightened and the insert may be readily lifted out of the space 11.

In Figure 3, I have substituted a screw 80 for prongs and provided a small nut to be threaded on the end of the screw. The screw is denoted 13^c and is designed to pass through an annular washer 13^a, and the nut is denoted 13^f and is designed to readily 85 engage or be disengaged from the screws.

My invention presents a number of very decided advantages among which the following may be mentioned:—By keeping in stock a limited supply of rings and a large 90 variety of inserts a jeweler is in position to quickly fill an order for almost any kind of ring. If a given type of ring proves to be popular, the jeweler has the means at hand for immediately filling orders without the necessity of ordering from the manufacturer and perhaps waiting several weeks for the order to be filled, as is now frequently the case. Moreover, owing to the 95 ready interchangeability of the inserts, the jeweler is not required to order large quantities of any particular kind of ring which may have but passing vogue and then find himself burdened with unsalable stock when the vogue has passed. Again, cases are frequent in which the owner of a ring would like a new one but hesitates to purchase 100 because of the cost, whereas if the appearance of the old ring could be changed at a moderate cost by the replacement of the 110

old insert by a different one the cost would not be an obstacle.

I claim:—

As a new article of manufacture, a finger ring having a space between the finger embracing opening and the periphery of the ring, posts within and extending trans-

versely of the space, an insert for said space, and prongs carried by said insert and adapted to be clinched about and un-clinched from said posts. 10

In testimony whereof I affix my signature.

ISAAC E. KALISHER.
